UNITED STATES PATENT OFFICE.

C. A. SCHULTZ, OF NEW YORK, N. Y.

STEAM-VALVE.

Specification of Letters Patent No. 23,714, dated April 19, 1859.

To all whom it may concern:

Be it known that I, C. A. SCHULTZ, of New York, in the county of New York and State of New York, have invented a new and 5 useful Improvement in Slide-Valves for Steam-Engines; and I do hereby declare that the following is a full, clear, and exact description of the construction and operation of the same, reference being had to the 10 annexed drawings, making a part of this specification, in which—

Figure 1 is perspective view; Fig. 2, a longitudinal elevation; Fig. 3, a plan.

The principle of my invention is to take 15 off the steam-pressure of slide-valves for steam-engines, which is done by having the following attachments made to a common slide-valve: A is the body of a common slide-valve, B B B B are four columns placed 20 one on each corner on the top of slide-valve A, C is a plate or top resting on columns B B B B, D is a cap fitted steam-tight on the plate or top C, but so as to allow the same to move freely up and down; four 25 holes are in the top or plate which run about half way into columns B B B B, to be used for spiral-springs E E E E. These

spiral springs are intended to press against cap D, which will bring cap D to bear against the top or cover of the steam-chest 30 and at the same time valve A against the face of the cylinder. The valve A, columns B B B B and top or plate C can be cast a solid piece or fitted together, and cap D fitted to it as above said. This cap D in 35 combination with spiral springs E E E E will serve as packing, so as to let no steam enter between cap D and the cover of the steam-chest. The steam will be between valve A and top or plate C and when made 40 the same area there will be the same pressure against top or plate C as there is against valve A, but this can be made to suit so as to give the valve A more or less pressure 45 against the face of the cylinder.

Claim:

The combined arrangement of the spiral springs and their inclosing columns, with the plate C, as, and for the purposes above described.

C. A. SCHULTZ.
